UNITED STATES PATENT OFFICE.

CHARLES A. SCHULER AND PHILIP W. STAERKLE, OF NEW YORK, N. Y.

AUTOMATIC TRAIN-STOP.

1,114,388.

Specification of Letters Patent.

Patented Oct. 20, 1914.

Application filed August 26, 1913. Serial No. 786,783.

To all whom it may concern:

Be it known that we, CHARLES A. SCHULER and PHILIP W. STAERKLE, citizens of the United States, residing at New York city, in the county of New York and State of New York, have invented certain new and useful Improvements in Automatic Train-Stops; and we do hereby declare the following to be a full, clear, and exact description of the invention, such as will enable others skilled in the art to which it appertains to make and use the same.

Our invention relates to devices for automatically stopping trains should the engineer fail to see the danger signal and attempt to pass thereby.

An important object of our invention is to provide a shoe slidably arranged in between the rails of a track and operated by the mechanism controlling a semaphore signal, that is adapted for engagement with means carried by the train, which will operate upon the controlling mechanism of the locomotive and consequently bring the train to a stop.

A further object of our invention is to provide a device of the above mentioned character which is simple as to construction and arrangement, reliable and efficient in its operation and cheap to manufacture.

The above and additional objects are accomplished by such means as are illustrated in the accompanying drawings, described in the following specification and then more particularly pointed out in the claims which are appended hereto and form a part of this application.

With reference to the drawings, wherein we have illustrated the preferred embodiment of our invention as it is reduced to practice, and throughout the several views of which, similar reference numerals designate corresponding parts: Figure 1 is a vertical section illustrating our device as it would appear in assembled operative position, and Fig. 2 is a plan view of the shoe that is slidably arranged between the rails.

Referring to the drawings by numerals, 1 designates a preferably wooden block that is suitably attached to the lower structure of a locomotive. This block 1 is designed to support a slideable tripping mechanism, in such a manner upon the locomotive as to cause the tripping mechanism to be in a position for engagement with a shoe arranged between the rails of a track and to be next described. The block 1 is provided

with an annular opening 2 that is disposed angularly with relation to the vertical axis of the block 1.

A tubular member 3 is mounted within the opening 2 and is provided at its upper and lower terminals with annular flanges 4 and 5 that are countersunk within the block 1. A shoe engaging member 6 having a rounded lower terminal 7 is slidably mounted within the tubular member 3 so that it is normally in its position for engagement with the shoe. A rod 8 is connected with the upper terminal of the member 6 in any suitable manner and extends outwardly to the upper terminal of the tubular member 3. The outer terminal of the rod 8 is pivoted as at 9 to a rod 10 that is pivotally secured as at 11 to some suitable part of the locomotive structure. A tubular washer 12 provided with a straight face 13 and beveled face 14 is loosely mounted upon the rod 8 so that the beveled face 14 is in engagement with the upper face of the annular flange 4.

A nut 15 is threaded upon the rod 8 and engages the straight face 13 of the washer 12 and it will thus be seen that the washer 12 and nut 15 in being arranged such as described serve to efficiently dispose and support the member 6. A helical spring 16 is mounted upon the rod 8, engages the under face of the nut 15 and the upper face of the member 6. This spring 16 serves to return the member 6 to its normal operative position as it will be compressed upon the upward movement of the member 6 and upon the completion of the upward movement of the member 6 the spring 16 will expand and return the member 6 to its normal position.

A cord or suitable flexible element 17 is secured as at 18 to one of the terminals of the member 10, rides upon a pulley 19 and is connected in any suitable manner to the controlling mechanism of the locomotive. The pulley 19 is suitably mounted to any convenient part of the locomotive frame.

The shoe for operating the above described mechanism consists of a rectangular block that is designated as an entirety by the numeral 20. This shoe 20 is provided with a beveled face 21 that is adapted for engagement with the rounded terminal 7 of the member 6, when the shoe is in a position for such operation. A pair of spaced supporting bars 22 are bolted or otherwise suitably secured to the ties longitudinally with relation to the rails and support a rec-

tangular plate 23 having certain of its edges 24 and 25 bent upwardly and inwardly so as to receive flanges 26 and 27 that are formed upon certain of the edges of the block 20, whereby the block is slidably mounted upon the plate 23.

- A bell-crank 28 is suitably mounted upon a supporting block 29 that is disposed upon one side of the rails. This bell crank 28 is 10 connected at its free terminals with a rod 30 that is suitably connected to the shoe 20, and to a rod 31 that is suitably connected to a semaphore mechanism so that when the semaphore arm is disposed in a danger or 15 stop position the shoe 20 will be in such a position that it will cause the member 6 to engage the beveled face thereof and operate to stop the train. It will thus be seen that when the shoe 20 is in a position to cause 20 the train to stop, that the semaphore arm is in its stop position and engagement of the rounded terminal 7 of the member 6 with the beveled face 21 of the shoe 20 will cause the member 6 to be pushed upwardly and 25 exert a pull upon the cord 17, which, as before stated is suitably connected to the controlling mechanism of the locomotive. The action such as described upon the cord 17 will serve to bring the locomotive to a stop. 30 The member 6 is pushed upwardly against the action of the helical spring 16 which serves to return the member 6 to its normal operative position upon the completion of the upward movement thereof.
- 35 It is apparent with reference to the drawings and foregoing description that should the engineer attempt to run by the stop or danger signal that the train will be brought to an immediate stop by the operation of the 40 mechanism hereinbefore described.

In practice, we have found that the form of our invention, illustrated in the drawings and referred to in the above description, as the preferred embodiment, is the most efficient and practical; yet realizing that the 45 conditions concurrent with the adoption of our device will necessarily vary, we desire to emphasize the fact that various minor changes in details of construction, proportion and arrangement of parts may be resorted to, when required, without sacrificing any of the advantages of our invention, as 50 defined in the appended claims.

What is claimed is:—

- 55 1. In a device of the character described the combination with a support adapted to be attached to a locomotive, of a shoe engaging member slidably mounted within said support and disposed angularly with 60 relation to the vertical axis thereof, means for operating said shoe engaging member

carried between the rails, said shoe engaging member operatively connected with the controlling mechanism of the locomotive, and means for holding said shoe engaging member in operative position comprising a washer having a straight face and a beveled face, a nut adapted for engagement with the straight face of said washer and a suitably stiff spring.

2. In a device of the character described the combination with a support adapted to be secured to a locomotive, of a shoe engaging member slidably mounted within said support and disposed angularly with relation to the vertical axis thereof, a rod connected with the upper terminal of said shoe engaging member and disposed above said support, a pivoted lever connected at one terminal with said rod, a flexible element connected with said pivoted lever, said flexible element adapted to be connected with the controlling mechanism of the locomotive, means for pushing said shoe engaging member upwardly carried between the rails, 85 a nut carried on said first named rod in spaced relation to the upper terminal of said shoe engaging member, and a spring mounted upon said rod and engaging the upper terminal of said shoe engaging member and 90 the nut.

3. In a device of the character described the combination with a support adapted to be secured to a locomotive and having an opening extending therethrough at an angle 95 to the vertical, of a tubular member mounted within said opening, said tubular member provided with annular flanges at its terminals, a shoe engaging member mounted within said tubular member, a rod connected 100 with the upper terminal of said shoe engaging member and extending upwardly from said support, said rod operatively connected with the controlling mechanism of the locomotive, a washer having a straight 105 face and a beveled face mounted upon said rod so that its beveled face engages the flange on the upper terminal of said tubular member, a spring mounted upon said rod, a nut threaded upon said rod engaging the straight face of said washer and the upper terminal of said spring, and means for operating said shoe engaging member carried between the rails of the track.

In testimony whereof we affix our signatures in presence of two witnesses.

CHARLES A. SCHULER.
PHILIP W. STAERKLE.
